UNITED STATES PATENT OFFICE.

RAPHAEL LEMIEUX, OF NEW BEDFORD, MASSACHUSETTS.

TENSION DEVICE.

Application filed May 27, 1924. Serial No. 716,241.

To all whom it may concern:

Be it known that I, RAPHAEL LEMIEUX, citizen of the United States, residing at New Bedford, in the county of Bristol and 5 State of Massachusetts, have invented certain new and useful Improvements in Tension Devices, of which the following is a specification.

This invention relates to certain new and 10 useful improvements in thread tensioning devices and more particularly relates to devices for tensioning thread in spooling machines.

The primary object of the present invention is to provide novel and improved means 15 for enabling the tension on the thread to be regulated as desired.

A further object of the invention is to provide tensioning means for the thread 20 which is of simplified construction, positive in operation and devoid of parts subject to derangement.

The invention has still further and other object which will be later set forth and 25 manifested in the course of the following description.

In the drawings:—

Figure 1, is a side elevation of the invention; 30 Figure 2, is a section on line 2—2 of Figure 1;

Figure 3, is a section on line 3—3 of Figure 1, and

Figure 4, is a section on line 4—4 of Figure 2.

In proceeding in accordance with the present invention a frame 1 of any suitable form is employed and which has a spindle 2 on which a bobbin 3 is mounted. The 40 thread from the bobbin passes vertically through guides 4 and 4', thence through the tensioning device, over a guide pulley 5 through a stationary guide 6 and then is wound on a spool, not shown.

The tensioning device forming the subject of the present invention includes a pair of vertically and oppositely disposed corrugated jaws or members 7 and 8, each pivotally mounted on a vertical pin 9', the latter being secured at its ends to the frame 1. The outer sides of the members 7 and 8 are relatively flared as indicated at 9 and 10 so as to form a divergent mouth to facilitate the introduction of the thread between the 55 tensioning jaws or the members. The inner sides of the members are provided with

relatively divergent wings 11 and 12, which latter are engaged by the curved nose 13 of a substantially Z-shaped actuating member 14. The member 14 is pivoted between its 60 ends at 15 to a part of the frame 1 and has its rear end 16 curved and engaged by the free end of the horizontal arm 17 of a substantially L-shaped lever, the vertical arm of the lever being pivoted at 18 to the frame. 65 The arm 17 of the lever is provided with a series of spaced perforations 19 in a selected one of which is received the hook-shaped end 20 of the shank 21 carried by a weight 22.

The jaw or member 8 is formed with thread guides 23 and 24 located at its ends so as to releasably receive and hold the thread against the undulating face of the jaw at the central portion of the latter. 70

In operation, the weight 22 is set in a selected one of the perforations 19 of the arm 17 of the lever according to the degree of tension to be exerted by the jaws on the thread T, the latter having an undulating 80 passage between or through the complementary corrugations of the jaws. The lever acts on the actuating member 14, causing the nose 13 of the latter to move vertically and wipingly engage and effect approaching 85 or permit receding movement of the jaws according to the setting of the weight.

From the above it will be apparent that the adjustment of the degree of tension of the jaws or the thread can be easily and 90 quickly effected by mere shifting of the weight, the operation of the entire mechanism being in full view of the operator so that the latter can readily ascertain whether proper functioning of the parts is being had. 95

What is claimed is:

1. In a thread tension device, a frame, a pair of vertical opposed corrugated jaws, a vertical pin connected at its ends to the frame and pivotally connected to the jaws 100 at points between the front and rear sides thereof, the front sides of the jaws being relatively diverged, relatively divergent wings on the rear sides of the jaws, one of the jaws having upper and lower thread 105 guides, a substantially Z-shaped actuating member pivoted to the frame and having a curved nose at one end thereof wipingly engaged with the wings, a substantially inverted L-shaped lever pivoted at the lower 110 end of its vertical leg to the frame and having the free end portion of its horizontal

arm engaging the opposite end of the actuating member, and a weight adjustable on the horizontal arm of the lever.

2. In a thread tension device, a frame, a pair of vertical opposed corrugated jaws, a vertical pin connected at its ends to the frame and pivotally connected to the jaws at points between the front and rear sides thereof, the front sides of the jaws being relatively diverged, relatively divergent wings on the rear sides of the jaws, one of the jaws having upper and lower thread guides, a substantially Z-shaped actuating member pivoted to the frame and having one end thereof formed to engage the wings, a lever pivoted to the frame and engaging the other end of the actuating member, and a weight adjustable on the lever.

3. In a thread tension device, a frame, a pair of vertical opposed corrugated jaws, a vertical pin connected at its ends to the frame and pivotally connected to the jaws at points between the front and rear sides thereof, the front sides of the jaws being relatively diverged, relatively divergent wings on the rear sides of the jaws, one of the jaws having upper and lower thread guides, an actuating member pivoted to the frame and engaging the wings to cause same to approach and to permit same to relatively recede, a lever engaging the actuating member, and a weight adjustable on the lever to tension the actuating member through the lever.

4. In a thread tensioning device, a pair of pivoted jaws having confronting thread engaging faces and having relatively divergent wings with free edges, a pivoted actuating member for the jaws having an end thereof shaped to form a substantially straight continuous nose which is common to and which wipingly engages each of the said free edges of the jaws, and means to tension said device.

5. In a thread tensioning device, a pair of pivoted jaws having confronting thread engaging faces and having relatively divergent wings with free edge portions, a pivoted actuating member for the jaws including a flat metal strip of a width in excess of the distance between said free edge portions of the wings having an end thereof curved downwardly to form a nose which wipingly engages each of the said free edge portions of the jaws, and means to tension said device.

6. In a thread tensioning device, a pair of jaws having confronting thread engaging faces, and an actuating device engaging the jaws to cause same to approach and to permit same to recede, a pivoted lever independent of said device and having a relatively long horizontal arm which latter engages said device and a weight adjustable along the length of the arm to regulably tension the lever and thereby said device.

In testimony whereof I affix my signature.

RAPHAEL LEMIEUX.
